UNITED STATES PATENT OFFICE.

JULIUS HERRIET, OF NEW YORK, N. Y., ASSIGNOR TO DAVID WOLFE BRUCE,
OF SAME PLACE.

DESIGN FOR FONT OF PRINTING-TYPES.

Specification forming part of Design No. 7,994, dated January 12, 1875; application filed December 8, 1874.
[Term of Patent 14 years.]

CASE A.

To all whom it may concern:

Be it known that I, JULIUS HERRIET, of the city, county, and State of New York, have originated and designed a new Pattern for Printing-Type, which I describe as follows:

The nature of my design is clearly shown in the accompanying typographic impression, to which reference is made, and which differs from every other kind of type in style and proportion. It consists of lower-case, capitals, points, and figures, having a heavy line of nearly uniform thickness surrounded by a

hair-line, and each letter having a half-diamond projecting from the top and bottom in appropriate parts, according to the pattern.

What I claim as my invention, and desire to secure by Letters Patent, is—

The design or pattern for a font of printing-types, herein shown and described.

JULIUS HERRIET.
